UNITED STATES PATENT OFFICE.

FRANCIS SEYMOUR, OF PATERSON, NEW JERSEY.

SPINNING, DOUBLING, AND TWISTING MACHINE.

No. 909,466.

Specification of Letters Patent.

Patented Jan. 12, 1909.

Application filed April 23, 1907, Serial No. 369,729. Renewed October 20, 1908. Serial No. 458,725.

To all whom it may concern:

Be it known that I, FRANCIS SEYMOUR, a citizen of the United States, and resident of Paterson, in the county of Passaic and State of New Jersey, have invented certain new and useful Improvements in Spinning, Doubling, and Twisting Machines, of which the following is a specification.

The object of my invention is to provide a new and improved spinning, doubling and twisting machine which is simple in construction, perfect in operation, composed of few parts and is stopped instantly when a thread breaks.

In the accompanying drawings, in which like figures of reference indicate like parts in all the figures:—Figure 1 is a side view of my improved spinning, doubling and twisting machine. Fig. 2 is a front view of the same. Fig. 3 is a horizontal sectional view on the line 2—2 of Fig. 2.

There are two spinning spindles 1 and one twisting spindle 2 in each set, all mounted on a common supporting rail 3 on which a greater or less number of such sets are mounted. The details of the spindles will not be described as they form no part of the present invention.

The spinning spindles 1 are each provided with a whirl or pulley 4 contacting with a driving belt 5 which is maintained in place by an idler 6. Each spindle 1 is mounted vertically on a laterally swinging plate 7 both of which turn around the base of the spindle 2, that is, the pivotal centers of the two spindles 1 coincide with the axis of the spindle 2. Said plates 7 are preferably made triangular as shown in Fig. 3 and their inner straight edges face each other. A loop spring 8 has one end secured in the swinging end of each of said plates 7 and presses these plates toward each other as far as a stop pin 9, between the two plates and projecting from the rail 3, permits.

A vertically movable rod 10 guided at its lower end in the rail 3 and at its upper end in the deck rail 11, is provided directly beneath the plates 7 with the bevel head 12, that is with a downwardly and outwardly inclined projection on each side. At its upper end the rod 10 has a shoulder 13 which can rest on the top of the deck rail 11, said rod passing through a slot in said rail permitting up and down movement of the rod and also movement toward and from the front edge of the rail, the upper end of the

rod being pressed toward the front edge of the rail by a flat spring 14 secured to the rod and resting against the rear end of said slot. A feed pulley 15 having a V shaped circumferential groove 16 is mounted on the rod 10. Two fallers 19, each terminating in an eye 20 are pivoted to the rod 10 and each faller is provided at its lower end with a toe 21 which can act upon and trip a tripper 22 pivoted to the rod 10 and having a laterally projecting pin 23 on which the toes 21 can act. The tripper 22 normally is in the position shown in Fig. 1 and out of the path of a tripping wheel 23^a having shoulders 24 which is constantly rotated in the direction from left to right. When a faller is released its upper end swings outward and its toe 21 swings the tripper 22 into position so that the shoulders 24 of the wheel 23^a can strike against the tripper and slightly lift the same and the rod 10.

The threads 25 from the two spindles 1 each pass through an eye 26 on the rod 10, then over guide rods 27, and between said rods through a faller eye. They then pass over a hook 28, and the doubled thread 28 passes from the hook 28^a around the feed pulley 15 through a guide eye 29 to the ring traveler on the ring 30 on the traverse rail 31 and from this ring traveler on the ring to the twisting spool 32 on the spindle 2.

33 represent the spinning spools on the spindles 1.

The feed pulley 15 is rotated frictionally from a smooth part 36 of the rim of the wheel 23^a. The twisting spindle 2 is driven from the spinning spindles by friction wheels 34 on the spinning spindles 1 engaging a grooved wheel 35 on the twisting spindle 2.

The operation is as follows:—Normally the parts are in the positions shown in Fig. 1, and the driving belt 5 is in contact with the whirls of the spinning spindles. The doubled threads are fed downward by the feed pulley 15 and at the same time the friction contact between the feed pulley 15 and wheel 23^a is broken. When a thread 25 breaks the corresponding faller drops or swings outward and the rod 10 is lifted by means of the tripper 22 and tripping wheel 23^a as stated, sufficiently to bring the shoulder 13 of the rod 10 above the top of the rail 11 over which it is pressed by the spring 14 whereby the rod is locked in raised position. As the rod 10 is moved

upward its beveled head 12 presses the two plates 7 from each other whereby the pulleys of the spinning spindles 1 are moved sufficiently to bring them out of contact 5 with the driving belt 5 and all three spindles are thus stopped instantly as the spindle 2 is driven only from the spindles 1. After the broken thread 25 has been tied the upper end of the rod 10 is pushed back 10 to disengage its shoulder 13 from the top of the rail 11 and the rod is then forced down and the spring 8 forces the two plates 7 toward each other whereby the pulleys of the spinning spindles are again brought 15 in contact with the driving belt and all three spindles are rotated and the contact between the feed pulley 15 and the wheel 23^a is established. The tied thread holds its faller in operative position as shown in Fig. 20 1 thus permitting the tripper to swing into its normal position in which it remains until a thread 25 again breaks and a toe of a faller tilts the tripper into the path of the shoulders on the wheel 23^a.

25 Having described my invention what I claim as new and desire to secure by Letters Patent is:—

1. In a spinning, doubling and twisting machine, the combination with a twisting 30 spindle, and two spinning spindles, the latter each mounted on a separate plate pivoted concentric with the twisting spindle, a driving belt in frictional contact with the spinning spindles, a spring pressing the pivoted plates toward each other, means for swinging the plates apart, and a stop motion for operating said means, substantially as set forth.

2. In a spinning, doubling and twisting 40 machine, the combination with a twisting machine and two spinning spindles, the latter each mounted on a separate plate, concentric with the twisting spindle, a driving belt in frictional contact with the spinning spindles, a spring pressing the plates toward each other, a movable rod between the plates and means on the same for forcing the plates apart and a stop motion for operating said rod, substantially as set forth.

50 3. In a spinning, doubling and twisting machine, the combination with a vertically movable rod, of two spinning spindles and a twisting spindle, two spinning spindle supports pivoted concentric with the twisting 55 spindle upon which supports said rod can act, a tripper on said rod, a tripping wheel, fallers for throwing the tripper in the path of the tripping wheel, and a feed pulley mounted on said rod, substantially as set forth.

60 4. In a spinning, doubling and twisting machine, the combination with a vertically

movable rod, of two spinning spindles and a twisting spindle, two spinning spindle supports mounted concentric with the twisting spindle upon which said supports said rod can act, a tripper on said rod, a tripping wheel, fallers for throwing the tripper in the path of the tripping wheel, and a feed pulley mounted on said rod, and means at 70 the upper end of said rod for automatically locking said rod in raised position, substantially as set forth.

5. In a spinning, doubling and twisting machine, the combination with two spinning 75 spindles and a twisting spindle, of a supporting plate for each spinning spindle, which plates are pivoted concentric with the twisting spindle, a belt in frictional contact with both spinning spindles, means for driving the twisting spindle by frictional contact with the spinning spindles, a spring acting on said plates to hold the spinning spindles in contact with the belt and a stop motion means for shifting the plates for 80 the purpose of breaking contact between the belt and spinning spindles, substantially as set forth.

6. In a spinning, doubling and twisting machine, the combination with two spinning 90 spindles and a twisting spindle, of a supporting plate for each spinning spindle, which plates are pivoted concentric with the twisting spindle, a belt in frictional contact with both spinning spindles, means for driving the twisting spindle by frictional contact with the spinning spindles, a spring acting on said plates to hold the spinning spindles in contact with the belt, a vertically 95 movable stop motion rod, means on the same for pressing the spinning spindle supporting plates apart, a tripper pivoted on the rod, a tripping wheel for engaging the tripper and mounted in a fixed bearing, fallers on the rod and a feed pulley mounted on the 100 rod and driven by friction from the tripper wheel, substantially as set forth.

7. In a spinning, doubling and twisting machine, the combination with spinning and twisting spindles, of a vertically movable 110 rod, means actuated by said rod for throwing the spindles out of operation, a feed pulley pivoted on the rod, and a friction pulley for driving said feed pulley, said friction pulley having rotary motion only, 115 substantially as set forth.

Signed at New York city in the county of New York and State of New York this 5th day of April A. D. 1907.

FRANCIS SEYMOUR.
